US00D608016S

(12) **United States Design Patent**
Grimshaw

(10) **Patent No.:** **US D608,016 S**
(45) **Date of Patent:** **** Jan. 12, 2010**

(54) **BOOTH ASSEMBLY**

(76) Inventor: **Nicholas Grimshaw**, 57 Clerkenwell Road, London (GB) EC1M 5NG

(**) Term: **14 Years**

(21) Appl. No.: **29/292,745**

(22) Filed: **Oct. 26, 2007**

(30) **Foreign Application Priority Data**

Apr. 27, 2007 (EM) 000715271

(51) **LOC (9) Cl.** **25-03**

(52) **U.S. Cl.** **D25/16**

(58) **Field of Classification Search** D25/1,
D25/15; D20/10, 39, 41; 52/36.1-36.2,
52/79.1; D6/421

See application file for complete search history.

CLAIM

The ornamental design for a booth assembly, as shown and described.

DESCRIPTION

FIG. 1 is a front perspective view of a first embodiment of a booth assembly showing my new design.

FIG. 2 is a front view thereof.

FIG. 3 is a left side view thereof.

FIG. 4 is a top view thereof.

FIG. 5 is a right side view thereof.

FIG. 6 is a back side view thereof.

FIG. 7 is a front perspective view of a second embodiment of a booth assembly showing my new design.

FIG. 8 is a front view thereof.

FIG. 9 is a left side view thereof.

FIG. 10 is a top view thereof.

FIG. 11 is a right side view thereof; and,

FIG. 12 is a back side view thereof.
